DESIGN FOR A WHEEL BALANCING DEVICE

Arthur N. Butler, Oakland, Calif., assignor to
Speedmaster Limited, Alameda County, Calif., a
copartnership composed of Jay Graves and
Arthur N. Butler

Application April 30, 1945, Serial No. 119,323

Term of patent 14 years

(Cl. D52—1)

To all whom it may concern:

Be it known that I, Arthur N. Butler, a citizen
of the United States and a resident of Oakland,
county of Alameda, State of California, have in-
vented a new, original, and ornamental Design
for a Wheel Balancing Device, of which the fol-
lowing is a specification, reference being had to
the accompanying drawing, forming part thereof.

Figure 1 is a side elevational view of the wheel
balancing device showing my new design.

Figure 2 is a top plan view of the device.

Figure 3 is a bottom view of the device.

I claim:

The ornamental design for a wheel balancing
device, substantially as shown.

ARTHUR N. BUTLER.
